UNITED STATES PATENT OFFICE.

KERRISON M. DAVIES, OF WILLIAMSON, NEW YORK, ASSIGNOR TO GEORGE W. COBB,
OF NEW YORK, N. Y.

STRING-BEAN SNIPPER.

1,136,588.

Specification of Letters Patent. Patented Apr. 20, 1915.

Application filed March 11, 1911. Serial No. 613,887.

To all whom it may concern:

Be it known that I, KERRISON M. DAVIES, of Williamson, Wayne county, and State of New York, have invented certain new and useful Improvements in String-Bean Snippers; and I do hereby declare the following to be a full, clear, and exact description of the same, reference being had to the accompanying drawings, forming a part of this specification, and to the reference-numerals marked thereon.

The present invention relates to string bean snippers, or apparatus for removing the ends of string beans, and has for its object to provide a machine adapted to operate successfully with beans of all lengths.

A further object of the invention is the provision of a machine which is entirely automatic in its operation, requiring only to be fed, and capable of a very large output.

To these and other ends the invention consists in certain improvements and combination of parts, all as will be hereinafter more fully described, the novel features being pointed out in the claims at the end of the specification.

In the drawings: Figure 1 is a top plan view of a machine showing a preferred embodiment of my invention; Fig. 2 is a view in vertical section on the line *a—a* of Fig. 1; Fig. 3 is a view in elevation, partly in section, showing the feeding mechanism of the machine, and Figs. 4 and 5 are detail sectional views showing the operation of the cutting devices.

The chief difficulty in machines of this character is to make it possible to snip off only the ends of the beans, no matter how long or short they may be, readily and efficiently, and to this end, in the embodiment of my invention as herein illustrated, the beans are supported alternately on their opposite end and are severed or cut at their supporting ends, so that the length of the bean in no way affects the operation of the machine. For this purpose, there are provided a plurality of supports 1 and a single support 2, arranged to successively support the opposite ends of a bean, suitable means being employed to maintain one end against one support, and movable to effect the shifting of the bean to its other end and on the other support.

The shifting means comprises a series of

guides preferably in the form of open ended hoppers 3 pivoted at 4 and having the supports 1 arranged in spaced relation to their lower ends. The beans may be fed individually into the guides in any convenient manner, as for example, by the devices hereinafter described, and are held in upright position while a suitable cutting device severs their supporting ends. Each guide is moved to inverted position after the lower end of its bean is severed, so as to discharge the bean into another guide, such as an open ended hopper 5 located above the support 2 and maintaining the opposite end of the bean against the support while a suitable cutting device severs the latter supporting end.

To rotate the guides, I may employ a rotary carrier in the form of a disk 6 journaled on a post 7 and having an upwardly extending sleeve 8 to which the driving mechanism is secured, the sleeve in the present instance, having a beveled gear wheel 9 secured thereto, the latter being arranged for engagement with a pinion 10 on a shaft 11 journaled in a bracket 12 which extends from the upper end of the post, the shaft 11 being driven by a band pulley 13.

The guides 3 and 5 may be arranged on the rotary carrier in two concentric annular series, the inner series of guides 5 preferably having laterally extending horizontal flanges 14 which are bolted to the carrier at 15, while the outer series of guides 3 may be pivoted to the inner series 5 as at 4, an adjustable stop 16 being carried by each one of the guides 5 to maintain the swinging guides 3 in proper vertical position, when lowered.

The guides 3 are each provided with a support 1 adapted to hold the bean until one end is severed, and while the guide is being raised to inverted position, the support being preferably in the form of a disk bolted to a lug 17 depending from the lower end of the guide to space the support from 100 said end.

Between the lower end of the guide 3 and the support 1, there is a space which receives the cutting device. The latter consists of a stationary horizontally arranged cutter or knife 18, adjustably secured to a post 19, and coöperating with the lower end of the guides during their movement past the cutter, the post 19 of the cutter being supported, if desired, on a table 20 arranged 110

beneath the carrier and secured to the post 7.

The inverting of the guides 3 may be effected by any suitable means, a cam 21 carried by a support 21^a being provided in the present instance and passing from a point slightly beyond the cutter 18 and below the rotary carrier, thence outwardly and upwardly and thence inwardly and upwardly to a point 22, where the guides 3 are inverted directly above the guides 5, so as to discharge their contents into the latter. The guides 3 from this point are moved to their normal positions by a suitable device 15 preferably comprising a cam 23 supported from the upright 7, an extension 24 on the cam 21 serving to guide the guides in their downward movement.

The beans are received in the guides 5 in an inverted position, their ends resting on the support 2, which in the present construction is carried by the table or frame 20 so that the guides 5 may travel thereover. The support is preferably of arcuate shape, and 25 extends from near the point 22 to an opening 24 in the frame or table 20, a cutting device, preferably in the form of a horizontally positioned knife blade or cutter 25 supported from the table by a post 26, being 30 positioned to engage the supporting ends of the beans as they pass the knife, resting on the support 2. When the end of the support 2 is reached, the beans, having nothing to retain them in the guides, are dropped 35 through the opening 24 into a suitable receptacle.

The mechanism herein shown for feeding the beans one by one to the guides 3 comprises a hopper 27 suitably supported by 40 brackets 27^a and having a rotary feed wheel 28 arranged at the bottom thereof. The feed wheel is provided with transverse pockets 29 in its periphery each adapted to receive a single bean, and coöoperating with the feed wheel is a roller 30 having a smooth 45 periphery and acting by its rotation in a direction opposite to the direction of rotation of the feed wheel to prevent crowding of the beans and to agitate and present them in a proper position to be individually received by the transverse pockets of the feed wheel. Arranged to receive the beans from the feed wheel is a chute 31 which is formed 50 so as to feed the beans in a vertical position to the guides, and having for this purpose a width at its upper end sufficient to permit it to receive the beans while they are horizontally arranged, and gradually decreasing in width toward its lower end, the 55 desired end being attained by forming one side wall so that the upper end of the bean is supported, while the opposite end is lowered, as shown at 32. The chute at its lower end rides on the upper ends of the guides 3, 60 and for this purpose swings about a pivot 65

33, the spaces between the guides 3 being closed by stops 34 which prevent the discharge of beans at this point. The driving of the feeding mechanism may be effected by providing a sprocket wheel 35 on the 70 drive shaft 11 and connecting this sprocket to a sprocket 36 on one end of the shaft of the roller 30, the other end of said shaft carrying a gear 37 which meshes with a gear 38 on the shaft of the feed wheel 28. 75

In operation, the beans are fed to the hopper 27 by hand or otherwise, and are deposited into the guides 3 on one of their ends which are snipped as the guides pass the cutter 18. The snipped beans are then inverted into guides 5 and during the passage of the latter over support 2, their other ends are snipped, after which, upon the end of the support being reached, they are discharged into a suitable receptacle. 80

I claim as my invention.

1. In a string-bean snipper, the combination with a pair of supports one of which is movable above the other, of guides for maintaining the beans upright upon the supports and cutters arranged to snip the ends of the beans while on the supports. 90

2. In a string-bean snipper, the combination with a pair of supports, of a pair of guides for holding a bean with opposite ends against the respective supports, one of said guide supports being movable to discharge its bean to the other guide in an inverted position, and cutters for operation on the supporting ends of the bean. 95

3. In a string-bean snipper, the combination with a plurality of traveling supports, of a plurality of guides movable with the supports, a feeding mechanism for depositing beans within the guides, a second set of 10 traveling guides, devices for moving the first set of guides to cause them to discharge into the second set, a support for beans in the second set of guides over which the latter travel, and cutters for removing the supporting ends of beans while in the guides. 11

4. In a string-bean snipper, the combination with a rotary carrier, of an annular series of guides carried thereby, an annular series of swinging guides also carried thereby, a series of supports carried by the movable guides, and a support over which the first named series of guides travel. 11

5. In a string-bean snipper, the combination with two series of guides, one of which is movable to discharge into the other, of a series of supports carried by and arranged in spaced relation to the movable guides, a fixed support over which the other series of guides pass, and cutters arranged to engage between the guides and the supports. 12

6. In a string-bean snipper, the combination with two series of open ended hoppers, the hoppers of one series being mounted to swing so as to discharge into the hoppers of 13

the other series, of a set of supports carried by the swinging hoppers in spaced relation to the lower ends of the latter, a fixed support over which the other series travels in spaced relation thereto, and cutters operating between the hoppers and the supports.

7. In a string-bean snipper, the combination with a rotary carrier, of a feeding mechanism, a set of open ended hopper shaped guides swingingly mounted on the carrier, supports carried by the lower ends of the guides in spaced relation thereto, a second set of open ended hopper shaped guides on the carrier, a device for causing the swingingly mounted guides to discharge into the other guides, a support over which the second set of guides travels during a portion of their movement, and fixed cutters for operating on the lower ends of beans while in each set of guides.

10 8. In a string-bean snipper, the combination with two series of guides, one series being mounted to swing and discharge into the other series, of a cam acting on the swingingly mounted series to effect their upward movement, supports carried by the swinging guides, a fixed support over which the other series travels, and cutters for operating on the beans while on the supports.

15 9. In a string-bean snipper, the combina-

tion with two series of guides, one series being mounted to swing and discharge into the other series, of a cam acting on the swinging series to effect their upward movement, a device engaging the swinging guides to return them to their normal positions, supports carried by the swinging guides, a fixed support over which the other series travels, and cutters for operating on the beans while on the supports.

10 10. The combination with a table and a rotatable carrier, of two annular series of guides on the carrier, one series being mounted to swing to discharge into the other, supports on the swinging guides, a cutter arranged on the table to sever the lower ends of the beans resting on the supports, a support on the table for the other guides, and a fixed cutter adapted to engage between the support and the guides.

15 11. In a string bean snipper, the combination with a series of movable guides, of a chute pivoted above the guides riding on the upper ends of the latter, and a cutter arranged to snip the ends of beans in the guides.
